Thos. A. Stiel.

UNITED STATES PATENT OFFICE.

ADAM DZIEMIAN, OF JERSEY CITY, NEW JERSEY.

CEMENT-FORMING APPARATUS.

1,113,317.

Specification of Letters Patent.

Patented Oct. 13, 1914.

Application filed January 22, 1912. Serial No. 672,659.

To all whom it may concern:

Be it known that I, ADAM DZIEMIAN, a subject of the Czar of Russia, residing at Jersey City, in the county of Hudson and State of New Jersey, have invented certain new and useful Improvements in Cement-Forming Apparatus, of which the following is a specification, reference being had therein to the accompanying drawing.

10 My invention relates to improvements in molding or forming apparatus and has particular reference to an adjustable cement mold adapted for use in forming cement floors in modern buildings.

15 Referring to the accompanying drawings I have illustrated in perspective partly broken away an application of my invention.

20 2, 3 and 4 represent the girders supporting the floor of a modern building, and 5 and 6 indicates the bottom of the mold surrounding the girders for holding the concrete in place. These are provided with brackets such as 7 through which pins such as 8 project and rest upon the flanges of the I-beams. 25 The pins 8 rest upon the pins 9 which may be introduced in any of the holes 10 thus making the mold adapted for different sizes of beams. 11 is another bracket suitably secured to the lower parts 6 of the mold and provided with standards such as 12 which may be adjustably secured therein by suitable means such as 13. The upper parts 14 of the molds are slidably adjustable as 30 shown.

35 15 and 16 are adjustable telescopic bars adapted to seat within the standards 12 and provided upon the upper face with suitable points or pins such as 17. These extend at 40 intervals between the molds as shown and serve to support suitable planking such as 18.

45 19 are telescopic bars adapted to engage the bars 15 and 16 to hold the same in position and also serve to provide support for additional reinforcement such as the plank 20. 21 and 22 are also adjustable telescopic connecting bars adapted to connect the

brackets 11 mounted upon the lower portions of the molds 5 and 6. 50

From this it will be seen that the apparatus may be fitted to beams of any size and of any separation being adjustable as aforesaid. After the apparatus is in position the planking is thrown across the supports 15, 55 16 and 20 and the cement with suitable reinforcing material is spread over the entire surface and around the beams within the molds and after the same has set, the molds may be shifted thus leaving the concrete 60 flooring in position.

Of course it will be understood that other means may be employed for adjusting and supporting the molds in position and various modifications may be made without departing from the spirit of the invention as set forth in the claims: 65

I claim.

1. A molding apparatus for floors comprising channel shaped molds adapted to be 70 adjusted around the floor beams, adjustable brackets carried by the sides of said channel shaped molds, transverse supports adapted to be supported by the brackets, and means located between the supports in combination with the brackets to brace said supports in lines parallel with said channel shaped mold. 75

2. A molding apparatus for floors comprising channel shaped molds adapted to be 80 adjusted around the floor beams, adjustable brackets carried by the sides of said channel shaped molds, transverse supports adapted to be supported by the brackets, and means located between the supports in combination 85 with the brackets to brace said supports in lines parallel with said channel shaped mold, said transverse supports comprising slidable sections adapted to be engaged against the adjacent walls of adjacent molds. 90

In testimony whereof I affix my signature in presence of two witnesses.

ADAM DZIEMIAN.
